UNITED STATES PATENT OFFICE.

LARS L. FURAN, OF THIEF RIVER FALLS, MINNESOTA.

RAZOR-STROP.

1,179,621.

Specification of Letters Patent. Patented Apr. 18, 1916.

Application filed December 27, 1915. Serial No. 68,764.

To all whom it may concern:

Be it known that I, LARS L. FURAN, a citizen of the United States of America, residing at Thief River Falls, in the county of 5 Pennington and State of Minnesota, have invented certain new and useful Improvements in Razor-Strops, of which the following is a specification.

My invention relates to an improved razor 10 strop, designed especially for use in connection with any safety or straight razors, the primary object of the invention being the provision of a device that may be operated either manually or by mechanical 15 power for stropping a razor to keep its edge in good condition for performing its required functions.

The invention consists in certain novel 20 combinations and arrangements of parts whereby the razor is movably held in such position that it may be presented, alternately, in contact with two revolving members carrying stropping surfaces, so that the two sides of the blade may be stropped 25 uniformly, as will be hereinafter more fully pointed out.

In the accompanying drawings I have 30 illustrated one complete example of the physical embodiment of my invention constructed according to the best mode I have so far devised for the practical application 35 of the principles of my invention.

Figure 1 is a plan view of the device complete. Fig. 2 is an enlarged sectional detail 35 view of the bearing for the rotary members. Fig. 3 is a sectional view of Fig. 1 on line 3—3. Fig. 4 is an enlarged detail view partly in section, showing the action of the shifting device for oscillating the razor in 40 order to present its sides successively to the revolving stropping members. Fig. 5 is a side view, parts in section, showing the oscillatable razor holder. Fig. 6 is an enlarged sectional view on line 6—6 Fig. 5. 45 Fig. 7 is a sectional view at line 7—7 Fig. 5.

In the preferred form of the invention as depicted in the drawings herewith I have illustrated the device as manually operated, 50 but it will be understood that other forms of power may be employed to operate the device and other forms or arrangements may be adopted for the mechanical parts. But to illustrate the device in convenient form 55 I have employed a supporting frame 1, preferably of rectangular shape, which may

be of metal or wood, or other suitable material, and is of required dimensions. The two side bars of this frame are connected by a cross bar or plate 2 which is rigidly fastened, as by screws, to the side bars and this plate 2 is the supporting member for the revoluble shaft or axle 3, which is journaled by means of the ball bearings, 4 to rotate or revolve in the bearings when power 65 is applied to the shaft or axle 3.

At 5 and 6 (Fig. 2) the shaft is formed with squared portions in order that the two hubs 7 and 8 may be fixed thereto to rotate with the shaft. These hubs are round disks 70 that carry the revolving members and the hubs are revolved through the medium of the crank, 9 attached at one end of the shaft.

The revoluble stropping devices comprise 75 two open center rings or round plates 10 11. fastened to the hubs 7 8 by means of the projecting lugs 12 and screws 13, the former integral with the hubs and the latter used to secure the lugs to the rings. The rings 80 are located adjacent each other and revolve simultaneously in parallelism, and the inner or adjoining face of each of these rings is provided with a leather or other soft covering suitable for stropping the edges of a 85 razor blade. These rings may be of wood or metal as desired, and where a fine finish is not desired for the edge to be sharpened, the leather face of the rings may be displaced and a coarser surface provided. In any 90 event it will be seen that the two parallel 95 revolving members are supported in the cross bar 2, and that they may be directly operated through the medium of the crank handle 9.

An old style or straight razor blade 14 is illustrated provided with the usual handle 15 into which it is adapted to fold, and this 100 razor and its handle are supported in position so that the blade is located between the two stropping disks 10 11 and so that it may be turned or oscillated to contact first with one stropping surface as 10' and then with the other surface 11' in order to uniformly 105 strop the edges of the blade. The razor blade and handle are retained in a casing 16, preferably of sheet metal and formed of proper shape to fit over the blade 14 at its back, and also provided with wings 16' at one end, to clasp the handle 15 of the razor. The casing is preferably of resilient metal 110 so that it sides may clasp about the razor 115

blade and the two wings 16' may clasp firmly about the razor handle, and thus hold the razor firmly in the casing. The casing is preferably formed with a rounded end or bearing 18 which is adapted to seat in a socket 19 in the cross bar 2. The rounded end 19 is the termination of a rib or rounded back edge 17 of the casing, and preferably this rib rests against a portion of the cross bar 2 as shown in Figs. 5 and 6. At a point indicated by the line 6-6 in Fig. 5 the rib 7 is slotted and formed with a rounded bar 18' about which the eye bolt 19' is fitted. This bolt is fixed in the bar 2 and its head or eye is slotted to permit movement of the bar 18' when the casing 16 is oscillated. The eye bolt holds the casing in place, but permits it to oscillate with the rounded bar 18' as its center of oscillation. The casing and razor may be held against oscillation by means of the latch 20 which is pivoted at 21 to a post 22 and has a resilient forked end 23 to fit over the rib 17 and wings 16' of the casing 16. In Fig. 1 the latch is unlocked and the casing and razor may be oscillated, but in Fig. 5 the latch is locked, and the razor and casing stand between and parallel with the two stropping disks so that the razor edges cannot contact with the stropping disks.

30 The casing and razor are oscillated through the medium of a yoke 23' which is provided with a cross bar 24 that is slidable through a sleeve 25, fixed transversely to the rib 17 of the casing. A second bar 26 extends 35 transversely of the yoke, and this arm or bar is connected through the spring 27 to the post 22 of the cross bar 2, as indicated at 28. The yoke 23' is slotted at 29 for the spring 27, and the free ends 30 of the yoke 40 project beyond the cross bar 24 in position to encounter the contact members or shoes 30^a or 30^b. By this contact the yoke is 45 caused to oscillate on the rounded end 18 as a center. The spring 27 tends to hold the yoke at its extreme position so that the razor blade edge is held against one of the leather rotary strops. The yoke is struck alternately by the shoes 30^a and 30^b and the 50 bar 24 is caused to slide through the sleeve 25, and it will be apparent that when the point 28, the point of attachment of the spring to the bar 26, and the center of oscillation are in alinement, the razor blade will 55 stand in line with all three of them, but when the yoke encounters one of the shoes the points are thrown out of alinement, and in Fig. 4 it will be seen that the spring is holding the razor blade against the stropping disk face 10'. These two shoes or contact members 30^a and 30^b act alternately on the yoke.

60 The shoe 30^a is carried at the end of an arm 31 which is pivoted at 32 in brackets 65 fixed to the hub 8, and the inner end 33 of

this arm travels in a cam groove 34 which is endless and passes around the wheel 35 rotatably fixed to the hub at 36. A forked arm 37 projects from the hub 8 and guides the movement of the arm 31.

70 The cam wheel 35 is freely rotatable on its journal 36, and is provided with four radial arms or spokes 38 which are in position to encounter the bent end 39 of a fixed bracket 40 attached at 41 to the frame 75 1. From this description it will be seen that as the disk 11 revolves it carries with it the cam wheel and pivoted arm 31. Now when the spokes, or rather a spoke of the wheel encounters the bent end 39 of the 80 bracket 40, it will be seen that the cam wheel is rotated one quarter turn, and the cam groove causes the arm 31 to move on its pivot, so that the shoe 30^a is in position to contact with the yoke 23' and move it on the rounded end 18 as its axis. The two shoes 30^a and 30^b are located diametrically opposite each other, and the shoe 30^b has a duplicate mechanism as arm 31' pivoted at 32' with its end 33' in the cam groove 34' of the wheel 35'. The wheel is journaled at 36' and the arm 31' is guided by the forked ends 37' while the spokes 38' encounter the bent end 39' of the bracket 40' which is fixed at 41' to the frame. Of course the cam 85 wheels and their cam arms with contact shoes are adjusted to act in fixed relation with each other so that as the stropping disks are revolved the razor blade has both its edges stropped during a single revolution of the stropping disks, and the continued rotation of the disks causes the razor blade to move or be oscillated, first to one side and then the other. It will be noted 90 that the blade is not located on a line radial with the center of revolution of the stropping disks, and because of this relationship of parts the motion of the stropping surface over the blade is from the heel of the blade toward the toe and the action is to 95 "draw" the blade in the same manner as that accomplished by hand. It will be seen 100 that both edges or sides of the blade are uniformly and effectively stropped, as the blade is alternately shifted from side to side by the action of the brackets and cam wheels. The leather stropping faces of the 105 disks may readily be renewed by removing the stropping disks from the hubs, and replacing the worn surfaces with fresh ones.

110 What I claim is:—

1. The combination with a pair of revoluble stropping disks, of a frame between the disks, a blade retaining casing oscillatably supported in the frame, a sleeve on the casing and a yoke having a bar slidable in the sleeve, means for contacting with said yoke to present the blade edge to alternate disks, and a resilient connection between the yoke and frame.

2. The combination with a razor strop-
ping device of an oscillatably supported
blade-retaining holder having a sleeve, a
transversely arranged yoke having a bar
3. slidable in the sleeve, a supporting frame,
and a spring having its ends attached to
the frame and yoke whereby the spring is
adapted to hold the parts out of alinement.
10 3. The combination with a rotary strop-
ping device, of a blade retaining casing os-
cillatably supported and its frame, a mov-
able member co-acting with said casing, and
a resilient connection between said member
and frame adapted to oscillate the casing
when its points of connection are out of 15
alinement with the axis of the casing.
4. The combination with a pair of rota-
table stropping disks and an oscillatable
blade retaining casing, of a revoluble cam
wheel carried by each disk, means for re-
volving each wheel, and a cam arm actuated
by each wheel adapted to operate said cas-
ing. 20

In testimony whereof I affix my signature.

LARS L. FURAN.
